UNITED STATES PATENT OFFICE.

ROBERT BROWN, OF STROUDSBURG, PENNSYLVANIA.

WASHING-MACHINE.

Specification of Letters Patent No. 24,612, dated July 5, 1859.

To all whom it may concern:

Be it known that I, ROBT. BROWN, of Stroudsburg, Monroe county, State of Pennsylvania, have invented a new and useful 5 Improvement in Washing-Machines; and I do hereby declare the following to be a full, clear, and exact description of the same, reference being had to the accompanying drawing and to the letters of reference marked 10 thereon.

My invention consists in a curved vibrating, trough, with bars at each end, in combination with a series of stationary bars, the said trough being guided by certain strips, 15 and the whole being constructed and arranged substantially as described hereafter, so that the clothes deposited in the trough at each side of the stationary bar may, as the trough vibrates, tend to turn over of themselves, thereby changing their position, so as to be compressed in different places between 20 the stationary and vibrating bars.

In order to enable others to make and use 25 my invention, I will now proceed to describe its construction and operation.

On reference to the accompanying drawing which forms part of this specification. Figure 1 is a side view of my improved washing machine; Fig. 2, a sectional elevation, and Fig. 3, a transverse sectional elevation.

Similar letters refer to similar parts throughout the several views.

A, and A', are two triangular frames connected together near the middle by the transverse strips, B, and B', and at the top by a rod C. To the latter is suspended, by means of the diagonal rods D, and D', a trough or vessel E, of the form represented in Figs. 1 40 and 2, the upper edge and bottom of the trough forming segments of a circle of which the rod C is the center. Two vertical bars H, and H', are connected at the top to the rod C, and near the middle to the cross-bars 45 B, and B', of the frame.

To the lower end of the rods H, and H', are secured a series of strips a, a, the lowest strip being as close to the bottom of the trough as possible without touching it, and 50 the sides of the strips being close to, but not in actual contact with, the opposite sides of the trough.

To the ends e and e', of the trough, are fitted boards F, F', the latter being so at-

tached to the diagonal braces of the frame so 55 as to be readily removed when desired. To the middle of the trough and near each end are a series of transverse bars h.

A curved strip i, is secured to the middle of each of the opposite triangular frames A, 60 and A', and a curved strip j, is also secured to each side of the trough. A projection on each strip i overhangs and fits against a projection on the strip j, so that the trough is guided during its movements. 65

Water, soap, or any of the washing compounds used in other machines are deposited in the trough, and the clothes to be washed are placed some on each side of the strips a, a, and between these strips and the 70 transverse strips h, h, of the trough. A swinging or vibrating motion is then imparted to the trough by hand, or by any suitable appliances, driven by any adjacent shaft, when the clothes on both sides will be 75 compressed alternately, between the stationary strips a, and the strips h, of the trough.

I am aware that washing machines have been made with curved stationary troughs and vibrating strips. In such machines 80 however the clothes are apt to be retained in one position, and consequently to be compressed repeatedly in the same place, rendering the operation tedious and ineffective and involving the necessity of changing the 85 position of the clothes by means of some suitable instrument. By so constructing the machine that the bars a, may remain stationary, while the trough vibrates, the clothes on each side are elevated alternately to such 90 a position that they naturally turn over presenting a different surface for compression at every movement of the cloth and inclosing within their folds more or less water which is forced through the fibers of the 95 fabric, thereby tending to rapidly and thoroughly cleanse the clothes.

In Fig. 2, s, s, represent two chambers which are situated between the transverse strips h, h, and the ends of the trough e, e', 100 into which the water escapes from the clothes when they are pressed. As the trough swings backward and forward, the strips (h, h,) being situated in such relation to the bars a, a, that they will pass between them, they press the clothes in between the bars a, a, and thus at the same time partially rub them and squeeze or press the water 105

from them, the water being allowed to escape into the chambers *s*, *s*, back of the clothes.

What I claim as new and desire to secure by Letters Patent is—

The arrangement, in the trough *E'*, of the chambers *s*, *s*, and transverse strips *h*, *h*, with the bars *a*, *a*, when the chambers stand behind the strips and the strips are placed in such relation to the bars *a*, *a*, that they will 10 pass between them and thus at the same

time press and rub the clothes, the several parts being constructed and operating substantially in the manner and for the purpose set forth. 15

In testimony whereof, I have signed my name to this specification in the presence of two subscribing witnesses.

ROBERT BROWN.
